UNITED STATES PATENT OFFICE.

OTTO LAMPE, OF HAMBURG, GERMANY.

TRACE-HOOK.

SPECIFICATION forming part of Letters Patent No. 292,922, dated February 5, 1884.

Application filed November 10, 1883. (No model.)

To all whom it may concern:

Be it known that I, OTTO LAMPE, of Hamburg, in the Empire of Germany, have invented certain Improvements in Trace-Hooks, 5 of which the following is a specification, reference being had to the accompanying drawings.

My invention relates to trace-hooks which are so constructed that the traces may be instantaneously released from the whiffletree without being obliged to back the horse or to move the carriage or vehicle toward the horse.

The invention will be fully described, and 15 then pointed out in the claim.

The invention is illustrated in the accompanying drawings, in which Figure 1 is a side view, partly in section, of a trace-hook constructed according to my invention, showing 20 the hook closed. Fig. 2 is a side view of the same, showing the hook open. Fig. 3 is a top view of the hook and one end of whiffletree, to which it is attached. Fig. 4 is a view like Fig. 1, but showing a slight modification.

25 Similar letters of reference indicate corresponding parts in the several figures.

This improved trace - hook, which is, by means of a screw-clamp, *m*, or other suitable means, attached to the end of a whiffletree, *S*, has at its front end a movable nose or beak, *A*, that is pivoted by a bolt or pin, *p*, to the body or stock *B* of the hook. The eye or ring of the trace is placed over this nose when the latter is in an open position, as shown in Fig. 35 2, after which the nose is turned back so far that its point rests on the body or stock of the hook, as shown in Figs. 1, 3, and 4, or until this point comes so near to the body that the eye or ring of the trace cannot slip out, in 40 which position a spring - catch engages the backwardly-prolonged root or base of the nose, and locks the latter so that it cannot open accidentally. The spring - catch consists of a

double-armed lever, *D*, which is partly received in a recess provided in the under side of the body *B* of the hook, and which is fulcrumed therein on a pin, *v*, secured in said body. The said lever extends longitudinally of the body, and its front end forms a catch, which enters into a notch, *e*, in the hinder end of the 45 prolonged root or base of the nose or beak when the latter is closed, while the back end of the said lever, that projects somewhat from the body of the hook, is formed into a finger or handle, by which it can be pushed upward 50 against a spiral or flat spring, *h*, placed between the body of the hook and upper side of the lever. This spring keeps the locked lever in position and keeps the hook in a closed condition, as shown in Figs. 1, 3, and 4.

For opening the nose and disengaging the hook from the trace, the finger or handle must be pushed upward, in consequence of which the front end of the locking - lever moves downward out of the notch *e* and unlocks the nose or beak, which latter is now free to turn and be thrown over the front part of the body *B*, after which the eye or ring of the trace will slip over the nose and off the hook.

What I claim as my invention, and desire to 70 secure by Letters Patent, is—

The combination of the body or stock *B*, provided with a recess in its under side, the nose or beak *A*, pivoted in the body or stock, and provided at its rear end with the notch *e*, 75 the double-armed catch-lever *D*, arranged longitudinally of the body or stock, pivoted in the recess in the under side thereof, and at its forward end engaging with the notch *e*, and the spring *h*, arranged between the under side 80 of the body or stock and the upper side of said lever, all substantially as herein described.

OTTO LAMPE.
